UNITED STATES PATENT OFFICE.

GUY F. MILLER, OF TRAVERSE CITY, MICHIGAN.

FIRE-ALARM SWITCH.

1,340,729.

Specification of Letters Patent. Patented May 18, 1920.

Application filed May 27, 1919. Serial No. 300,068.

To all whom it may concern:

Be it known that I, GUY F. MILLER, a citizen of the United States, and a resident of Traverse City, in the county of Grand 5 Traverse, in the State of Michigan, have invented a new and Improved Fire-Alarm Switch, of which the following is a full, clear, and exact description.

This invention relates to automatic fire 10 alarms and has particular reference to switches involving the use of some fusible device which normally holds the switch points separated, but which when in proximity to high temperature such as may be 15 incident to the starting of a fire in a building will burn or so weaken as to permit the switch points to come together and complete a circuit which may include any suitable audible, or other alarm devices.

20 Among the objects of the invention is to provide a fire alarm switch of an unusually simple, cheap, and yet efficient nature; one which may be introduced at any point or points along a double twisted insulated wire 25 so that the presence of fire or dangerous heat in any part of a building may make itself manifest at such place and a record indicated thereof at any desired headquarters such as an office, sleeping apartment, or 30 watchman's station, and a further object is to provide a safety switch of the character indicated that is adapted to be easily manipulated in installation and which will retain its virtue throughout a long period 35 of years.

With the foregoing and other objects in view the invention consists in the arrangement and combination of parts hereinafter described and claimed, and while the invention 40 is not restricted to the exact details of construction disclosed or suggested herein, still for the purpose of illustrating a practical embodiment thereof reference is had to the accompanying drawings in which like 45 reference characters designate the same parts in the several views, and in which—

Figure 1 is a perspective view of the safety switch prior to its attachment to the line wires and with the dust protecting cap 50 omitted.

Fig. 2 is a plan view of the same after it is attached to the line wires but before taping; and

Fig. 3 is a detail view in longitudinal section indicating the normal relation of the 55 two switch points or blades.

Referring now more specifically to the drawings I show my invention as comprising a block or body 10 of fiber, porcelain, hard rubber, or other suitable durable insulation. Said body is indicated as rectangular in general form and provided along one side with a long recess or notch 11.

12 indicates a stationary switch blade fastened in any suitable manner upon one end 65 of the body 10 and having a lip 12' bent inward into the recess 11 adjacent to one end of the recess. The edge however of the lip is spaced materially from the bottom of the recess. The other switch blade is indicated 70 at 13 one end of which is secured upon the opposite end of the body 10 from the blade 12 while the main portion of the blade 13 extends along the recess 11 and with its free end lying within the space between the lip 75 12' and the bottom of the recess and spaced from the aforesaid edge of said lip. Any suitable material of good conductivity may be used for these blades but I prefer phosphor bronze because such material is well 80 adapted to retain the elasticity of the metal indefinitely.

Any suitable means of an automatically reliable nature may be employed to hold the flexible blade 13 out of contact with the 85 rigid blade 12. To this end I employ a clip 14 shown as in the form of a U straddling the middle portion of the body and having the legs thereof extending past the edges of the blade 13 and connected to an inflammable retainer 15 shown as in the form of 90 a flat piece of celluloid having reduced ends or points 15'. This retainer lies flat against the outer face of the blade 13 and is preferably provided with holes 16 95 through which the leg portions of the clip 14 are passed and clenched or bent over on the outer face of the retainer. This clip may be made of wire or any other suitable material strong enough to hold the retainer 100 close enough to the body 10 to keep the points of the springs separated as clearly shown in Fig. 3. The celluloid strip or its equivalent constituting the retainer is sufficiently stiff and strong to hold indefinitely 105 to intended shape and prevent the contact between the two blades 12 and 13. The clip 14 is of a permanent nature and so the device will retain the form or position indicated indefinitely. In order to prevent 110 the accumulation of dust on or between the contact points or any other conditions that

might prevent the proper operation of the switch in case of an emergency I provide a covering which may be in the nature of a cap 17 made of thin sheet celluloid or other inflammable material but of a permanent nature when not exposed to heat. This cap is fitted over the recessed portion of the body, the adjacent contact points, the clip, and the main portion of the retainer, leaving however the points 15' of the retainer projecting and exposed. The shape of the body and the portions of the blades rigidly secured to its ends adapt the cap for fitting closely so as to carry out the purpose thereof.

As one means for securing the contact blades to the body I provide for each of them a conductor wire 18 one end of which is passed through the fixed end of the blade 20 and the adjacent end of the body and then clenched or otherwise fastened on the opposite side of the body. This conductor serves therefore two immediate purposes,—first, to lock the blade in place, and secondly, as a 25 connector between the switch device and a line wire indicated at 19.

All of the parts are made of relatively cheap, standard, and easily acquired materials and they are formed and assembled 30 with a minimum amount of expense.

In the practice of the invention I employ a double twisted main line comprising the two wires 19 having a covering of insulation 20 which may be extended for any desired 35 distance or through any number of rooms or apartments. One end of the line wire obviously will be connected with any suitable battery or other source of energy and some alarm device such as a gong which features are so common and well understood 40 that they are not illustrated.

The double wire may be untwisted slightly at any desired point so as to separate the wires 19 each of which will then be stripped 45 for say one-half an inch for the connection of the conductors 18 which may be done by simply twisting the loose ends thereof around the bared wires 19. To make the connections permanent they are preferably 50 soldered and wrapped with tape in the manner well understood in the electrical art. The switch device as a whole is made flat, and having the conductor or connecting members exposed from the ends of the body 55 it may be easily attached to the line wire as described without any attention on the part of the electrician in installing it. These devices are made and sold so cheaply that they may be inserted in or along the double

wire at every six feet or wherever desired. 60 Obviously the alarm devices may be so constructed that the location of the fire may be indicated as result of the operation of any of the automatic switches. In the event of fire in proximity to the inflammable material 15 or 17, it would be most likely to make itself manifest at 15', one or both of such points would become ignited and immediately cause the burning of the retainer 15 and the release of the movable or flexible 70 blade 13 whose free end would then engage the lip 12' and complete the circuit.

I claim:

1. The herein described safety switch comprising a rigid body of insulation having 75 a recess formed in one side between and remote from the ends of the body, a pair of contact blades secured to the ends of the body on the recessed side and having their ends projecting into the recess, one of the 80 blades being shorter than the other and terminating in a lip directed inward toward the bottom of the recess and spaced therefrom, the other blade being longer and flexible and having its free end in the space between said lip and the bottom of the recess, means of a rigid nature embracing the body and the flexible blade and serving to normally hold said blade spaced from the lip, 85 said holding means including an inflammable retainer, means to electrically connect the body and blades to line wires and hold the switch in service, and a protecting device embracing the central portion of the body, the switch points, and the main portions of 95 the holding means for the flexible blade, to prevent failure of the switch because of dust or like conditions.

2. In a safety switch, the combination of 100 a body of insulation, a pair of switch blades secured to remote portions of the body, said blades having ends adapted to engage each other and one of the blades being resilient, 105 a clip embracing the body and the resilient blade, a retainer of inflammable material co-operating with the clip to hold the resilient blade spaced from the other blade whereby when the retainer becomes ignited it will burn and release the resilient blade permitting it to engage the other blade and establish 110 a circuit through them, and connector wires extending through the blades and the body and serving thereby to secure the blades to the body and establish electrical connection between the blades and any devices to which the connectors may be secured. 115

GUY F. MILLER.
